Primary Examiner — Cathron Brooks

Assistant Examiner — Teddy Falloway

(57) **CLAIM**

The ornamental design for a bra storage device, as shown and described.

DESCRIPTION

FIG. 1 is a front view of a bra storage device showing my new design;

FIG. 2 is a rear view of the bra storage device;

FIG. 3 is a left side view of the bra storage device, a right side view being a mirror image thereof;

FIG. 4 is a top view of the bra storage device;

FIG. 5 is a bottom view of the bra storage device;

FIG. 6 is a top front side perspective view of the bra storage device;

FIG. 7 is a cross-sectional view taken along line 7-7 of FIG. 6;

FIG. 8 is a cross-sectional view taken along line 8-8 of FIG. 6; and,

FIG. 9 is a partial cross-sectional view taken along line 9-9 of FIG. 8.
